UNITED STATES PATENT OFFICE.

THOMAS WEEPLE, OF OAKLAND, NEW JERSEY.

SMOKELESS FUEL.

SPECIFICATION forming part of Letters Patent No. 759,783, dated May 10, 1904.

Application filed June 3, 1903. Serial No. 159,949. (No specimens.)

To all whom it may concern:

Be it known that I, THOMAS WEEPLE, a subject of the King of Great Britain, and a resident of Oakland, in the county of Bergen and 5 State of New Jersey, have invented a new and Improved Smokeless Fuel, of which the following is a full, clear, and exact description.

My invention relates to a process of producing smokeless fuel from carbonaceous substances, by which I am able to produce a clear-burning fuel of high caloric value which burns freely without emitting black smoke and which yields a very small percentage of ash.

According to my invention I employ a simple method of treating such carbonaceous substances as bituminous coal, coal-dust, oil residue, and the like as will produce a fuel that will burn free from "black smoke" during the process of combustion, while at the same 20 time retaining all its caloric properties, thus making the fuel especially available for domestic and steam purposes.

I take the crude coal as it comes from the mines and pass it through a "breaker" or 25 other apparatus by which the largest lumps of coal are reduced to sizes not exceeding the size known commercially as "egg-coal." The resulting product is now passed through a series of grading-screens, which mechanically 30 separate the mass into the several commercial sizes known as "egg," "stove," "chestnut," and "pea" coal for domestic and steam purposes. The fine dust obtained by the screening and grading of the coal is utilized in the 35 manufacture of "briquets," a suitable binder being employed, the proportions, by weight, being ninety-nine per cent. of coal-dust to one per cent. of silicate of soda or common clay as a binding medium. After having 40 screened and graded the coal the mass, either separately or collectively, is deposited into a treating tank or receptacle of desired capacity and construction, said tank being preferably equipped with suitable heating appliances, such as devices for utilizing the heat 45 present in steam and hot air. The mass of coal in the tank is covered by or submerged in water supplied to the tank, and the water is heated to a boiling temperature by the

steam heating appliances. The mass or 50 charge of coal is thus subjected to a boiling process, which is the important step of my invention, and during this step in the treatment of the coal, which may continue from eight to ten hours, more or less, the mass undergoes a chemical reaction, becomes dehiscent, and yields up the volatile and other impurities of the product, the same being held in suspension and solution by the liquid-bath. The water is now drawn off from the charge 55 by emptying the tank, and the purified coal is subsequently and thoroughly dried by the application of steam heat or hot air while it remains in the tank, after which the treated charge is discharged from the tank in a suitable 60 way, the product being commercial coal.

I have discovered that the treatment of coal in the manner described secures a chemical change in the condition of the product, such change resulting in the cracking or disintegration of the coal and the liberation of the deleterious volatile matter which in the process of combustion evolves black smoke.

Having thus described my invention, I claim as new and desire to secure by Letters Patent — 75

1. The method herein described of producing smokeless fuel, which consists of boiling soft coal in water, whereby the mass becomes dehiscent and deleterious volatile matters are 80 eliminated.

2. The method herein described of producing smokeless fuel, which consists in boiling soft coal in water, and subsequently drying the coal.

3. The method herein described of producing smokeless fuel, which consists in charging a tank with a mass of soft coal, and immersing the coal in water, boiling the charge of soft coal for a predetermined length of time, separating the water and the coal, and finally 90 drying the coal by the application of heat.

In testimony whereof I have signed my name to this specification in the presence of two subscribing witnesses.

THOMAS WEEPLE.

Witnesses:

ABRAM G. McNOMEE,
BRAINARD W. JOHNSON.
